UNITED STATES PATENT OFFICE.

PAUL E. JOHNSON, OF CHICAGO, ILLINOIS, ASSIGNOR TO PAUL E. JOHNSON, INC., OF CHICAGO, ILLINOIS, A CORPORATION OF ILLINOIS.

DESIGN FOR A THERAPEUTIC LAMP.

Application filed April 6, 1927. Serial No. 21,482. Term of patent 14 years.

To all whom it may concern:

Be it known that I, PAUL E. JOHNSON, a citizen of the United States, residing at Chicago, in the county of Cook and State of Illinois, have invented a new, original, and ornamental Design for a Therapeutic Lamp, of which the following is a specification, reference being had to the accompanying drawing, forming a part thereof.

The drawing shows a side elevational view of one position of a therapeutic lamp illustrating my new design.

I claim:

The ornamental design for a therapeutic lamp substantially as shown.

PAUL E. JOHNSON.
